CLAIM

The ornamental design for a tray assembly for a dispensing container, as shown and described.

DESCRIPTION

FIG. 1 is a top, front perspective view of the new design for a tray assembly for a dispensing container, the tray assembly having a transparent cover portion;

FIG. 2 is a top, rear perspective view thereof;

FIG. 3 is a top plan view thereof;

FIG. 4 is an exploded front view thereof; and,

FIG. 5 is an exploded rear view thereof.

The broken lines shown herein depict environmental subject matter only and form no part of the claimed design.

1 Claim, 5 Drawing Sheets
